United States Patent Office.

WILLIAM M. IRVINE AND ALFRED H. MOSES, OF MONTGOMERY, ALABAMA.

Letters Patent No. 81,784, dated September 1, 1868.

IMPROVEMENT IN VENTILATORS FOR HATS.

The Schedule referred to in these Letters Patent and making part of the same.

TO ALL WHOM IT MAY CONCERN:

Be it known that we, WILLIAM M. IRVINE and ALFRED H. MOSES, of Montgomery, in the county of Montgomery, and State of Alabama, have invented certain new and useful Improvements in Hats; and we do hereby declare that the following is a full, clear, and exact description thereof, reference being had to the accompanying drawings, and to the letters of reference marked thereon, which form a part of this specification, and in which—

Figure 1 represents a plan view of a hat with our improvement attached, and

Figure 2 is a perspective of the band.

A band of metal, A, or other suitable material, about one inch wide, is formed into a ring to suit the shape of the head. One side of the band is punched with small holes, *c c*, suitable for sewing the band or ring to the inside of the side of a hat. The band is divided into two pieces, by cutting it at both sides, a little in front of the centre; we also separate the band in front and back, and hold the parts together by buttons *a a*, as shown in fig. 1.

The front portion of a band, A, fig. 2, has a longitudinal slot, C, near each end, about one-eighth of an inch wide, and about one inch long. One end of the band B is perforated with a hole, to allow a small screw, *e*, to pass through; the screw also passes through the slot, and screws into and through a nut on the outside of the slot, in the end of the band A, at C, when the ends of the bands are lapped over each other. The other end of the band B has a slot about one-eighth of an inch wide and an inch long. The end of the band runs into a flat tube, E, the tube being firmly secured to the hat by sewing or otherwise. The end of the tube is perforated by a small hole, to allow a screw to pass through. The screw passes through slot in end of band B, and into a nut on outside of tube E. The screws *e*, which pass through the ends of the band A at C, reach nearly to the inside of the hat. A long nut, perforated by small holes in its sides, to admit the point of an instrument for turning it, fits over each of the screws at C.

The brass tube E has an ear at one end, which is pierced with a small hole to allow a screw, *d*, to pass through, which screw also passes through slot C, in end of band A, and into a nut on outside of slot.

When the band or pieces of band are sewed in the hat on the sides of the inside, a space for ventilation is left between the hat and the band, both in front and behind. The band comes in direct contact with the sides of the hat.

When complete, the band may be covered with leather or other suitable material, in which small holes are left for the purpose of working the screws.

Mode of Using.

By loosening the screws which pass through the slots in the pieces of band, the size of the ring may be increased or diminished, to suit heads of different sizes, and secured in place by again tightening the screws.

By taking out the screws which pass through the slots C C, the front portion of band A may be entirely removed, and the requisite pressure on the temples to support the hat may be obtained, by turning the nuts on screws, which pass through end of band B and ear of tube E; or by loosening the screws which pass through slots C C, the portion of band A may be turned up at or nearly at right angles, adjusted and secured by again tightening the screws, in which position it would still bear a proportion of the weight of the hat by resting on top of the head; the object being in both cases to support the hat comfortably on the head, without any portion of it coming directly in contact with the forehead.

We do not claim a simple ring or band when used inside of a hat for ventilation.

Claims.

1. We claim a band or ring so constructed and arranged on the inside of a hat that it may be adjusted to different-sized heads, substantially as described.
2. We claim the band A, constructed in either one or more parts, and furnished with tubes *e* and *a*, slots C, and tube E, all arranged in the manner and for the purposes set forth.

In testimony that we claim the foregoing as our own, we affix our signatures in the presence of two witnesses.

WM. M. IRVINE,
ALF'D H. MOSES.
